UNITED STATES PATENT OFFICE.

ARCHIBALD S. CUBITT, OF SCHENECTADY, NEW YORK, ASSIGNOR TO GENERAL ELECTRIC COMPANY, A CORPORATION OF NEW YORK.

CURRENT-RELAY.

949,997.

Specification of Letters Patent. Patented Feb. 22, 1910.

Application filed April 17, 1906. Serial No. 312,071.

To all whom it may concern:

Be it known that I, ARCHIBALD S. CUBITT, a subject of the King of Great Britain, residing at Schenectady, in the county of 5 Schenectady, State of New York, have invented certain new and useful Improvements in Current-Relays, of which the following is a specification.

The present invention relates to current 10 relays and has for its object to improve and simplify the construction of relays and render their operation uniform and reliable.

In one of its aspects the present invention relates particularly to relays having a coil 15 which is primarily an actuating coil and a second coil which is primarily a holding coil. A relay of this character is shown in Patent No. 798,842 granted on August 29, 1905, on an application filed by George H. Hill, 20 wherein a "combined checking and overload relay" controls the automatic progression of a number of speed-controlling switches in a system of control for electric motors. There are two coils on this relay: one adapted to 25 lift the plunger in order to break the actuating circuit for the contactors; and another arranged in the motor circuit and adapted to prevent the plunger from dropping and completing the contactor actuating circuit 30 whenever the motor current exceeds a predetermined value. It will be seen that since the two coils are acting on the same plunger, the plunger will be lifted more quickly when the motor circuit is energized than where 35 there is no current flowing in the motor circuit. And similarly, variation in the motor current varies the lifting effort upon the plunger. It is desirable, however, to have a relay operate uniformly under all conditions, and therefore the present invention 40 contemplates means for neutralizing the effect of the holding coil during the time it is not required. This is accomplished by separating the two coils by a washer of magnetic material and so proportioning the plunger that when it is in its lowermost position there is practically no tendency on the part of the holding coil to lift it, the magnetic lines being shunted through the 45 washer.

The present invention also comprises other features of construction which cheapen and simplify relays, render them more efficient and provide for ready adjustment.

50 The several features constituting the pres-

ent invention, together with their objects and advantages, will more clearly appear from the following detailed description taken in connection with the accompanying drawing, wherein—

Figure 1 shows in cross-section a preferred form of relay embodying the various novel features of my invention; and Fig. 2 shows the same relay in side elevation.

Reference being had to the drawing, 1 indicates a frame of magnetic material within which are arranged coils 2 and 3, the coil 2 being illustrated as made up of a heavy conductor and the coil 3 as comprising a fine conductor. These coils are placed within the frame one above the other and with their central openings in alinement. A piece of magnetic material 4, which may form part of the frame 1 but which is conveniently made separate therefrom, is arranged between the adjacent ends of the coils 2 and 3. The member 4, together with the portions of the frame surrounding the coil 2 and the plug 5 secured to the frame and extending well down into the coil 2, form an almost complete magnetic circuit for this coil, to such an extent at least that there is very little leakage below the member 4.

6 is the plunger of the relay and this plunger comprises a rod 7 passing up from beneath the frame 1 through the interior of the coils through the plug 5. The rod 7 carries at its lower end a movable contact member or disk 8 and at its upper end the movable member 9 and the piston of a dash-pot 10. A sleeve 11 of magnetic material is secured to the plunger rod at such a point that, when the plunger is in its raised position, the upper end of the sleeve abuts against the lower end of plug 5, and when the plunger is in its lower position the top of the sleeve is located somewhat beneath the member 4. A second sleeve 12 is screw-threaded upon the lower end of the rod 7 and is so located that when the plunger is down the major portion of this sleeve lies below the lifting coil. It will be seen that by adjusting the position of the sleeve 12 on the rod and thereby varying its position with relation to the field of the lifting coil, the operation of the relay may be changed.

Assuming that the plunger of the relay is down, then if both of the coils are energized, it will be seen that while the effect of the holding coil 2 will be practically nothing, 110

since but few of the magnetic lines surrounding this coil stray to the sleeve 11, the plunger will, however, be lifted through the action of the coil 3, since the sleeve 12 will be drawn up in order to reduce the air-gap in the magnetic circuit of the lifting coil. As soon as the plunger has been lifted, however, the holding coil becomes effective, since the presence of the sleeve 11 completes the small gap in the magnetic circuit of this coil. The member 4, it will be seen, operates to produce the same effect as contacts which normally open-circuit or short-circuit the coil 2.

15 Although the relay may be used for other purposes, it is particularly adapted for controlling a circuit; in which case the movable member of the circuit-controlling switch may conveniently be carried upon the lower end of the plunger, as previously stated. This movable switch member preferably consists of a disk of magnetic material which co-operates with fixed contact pieces 13 and 14, also composed of magnetic material. The circuit which is controlled by the contacts 8, 13 and 14 also passes through two blow-out spools 15 and 16 surrounding the fixed contacts and, when current is flowing, magnetizes them. It will thus be seen that when current is flowing through the contacts they are magnetically held in engagement with each other against the pull of the plunger; and, by making the disk 8 loose upon the plunger and supporting it upon a spring 17, the plunger may move almost to its extreme upper position before the contacts are separated from each other; and, when so separated, the spring 17, which has been under tension, throws the disk upwardly so as to make a quick break. This is of especial advantage where the circuit containing the lifting coil is broken by the relay contacts, since it insures the operation of the plunger into the field of the holding coil before the circuit of the lifting coil is interrupted.

20 The fixed contacts may conveniently be made of sheet metal having body portions 13^a and 14^a arranged parallel to the line of movement of the plunger, and in-turned lips 13^b and 14^b with which the contact disk is adapted to co-operate. This construction obviates the necessity of separate pole-pieces and arc deflectors, since the fixed contacts 25 act also as pole pieces and arc deflectors. Furthermore, since the fixed contact members are in electrical connection with the blow-out coils, the entire device may be constructed cheaply and compactly for the reason that the fixed contacts are at the same potential as their corresponding blow-out coils and there is, therefore, no necessity for careful insulation, except between blow-out coils and ground. This latter insulation is, however, amply provided by the slab of insulat-

ing material 18 upon which the various parts are supported.

25 Although I have described in detail a preferred form of relay and one embodying all the various features of my invention, it will of course be understood that the relay may take other forms and the various features may be used together or independently of each other as occasion may require, and I, therefore, do not desire to be limited to the particular construction and organization of parts illustrated except to the extent particularly pointed out in the appended claims.

30 What I claim as new and desire to secure by Letters Patent of the United States, is:

1. In a relay, a pair of coils, a magnet frame surrounding said coils, a transverse frame member separating said coils, and a movable plunger arranged to operate within said coils, said plunger having a portion 35 adapted to be acted upon by one of said coils and lying normally on the side of said transverse frame member opposite that coil.

2. In a relay, a pair of coils arranged in alinement with each other, a frame of magnetic material surrounding said coils, a transverse frame member separating said coils from each other, and a plunger having a portion 40 lying normally on one side of said transverse member and adapted to be moved 45 into the coil on the opposite side of said member upon the energization of the relay.

3. In a relay, a lifting coil, a holding coil, a frame of magnetic material surrounding said coils and having a transverse member 100 located between said coils, and a plunger of magnetic material supported within said coils for movement from the side of said piece of magnetic material on which said lifting coil is located to the side of said 105 piece of magnetic material on which said holding coil is located.

4. In a relay, a lifting coil, a holding coil in axial alinement with said lifting coil, a frame of magnetic material surrounding 110 said coils, said frame having a transverse member separating said coils from each other, and a plunger of magnetic material supported for movement within said coils having a portion lying normally within the 115 lifting coil which is moved into the holding coil when said lifting coil is energized.

5. In a relay, a pair of axially alined coils, a plunger having a portion adapted to be acted upon by one of said coils and lying 120 normally out of the field of said latter coil, a second plunger portion adapted to be acted upon by the other coil and lying normally in position to be influenced by that coil, and means for moving said latter plunger portion toward and from the other plunger portion.

6. In a relay, a pair of coils arranged in axial alinement, a frame of magnetic material surrounding said coils, a transverse 130

- frame member separating said coils, a plunger having a portion adapted to be acted upon by one of said coils and lying normally on the side of said transverse member opposite said latter coil, a second plunger portion adapted to be acted upon by the other coil, and means for adjusting the position of said latter plunger portion with relation to the other plunger portion.
- 10 7. In a relay, a pair of coils arranged in axial alinement, a frame of magnetic material surrounding said coils, a transverse frame member separating said coils from each other, a plug extending from one end 15 of said frame into one of the coils and toward said transverse member, and a plunger having a portion arranged to be acted upon by the latter coil and a second portion arranged to be acted upon by the other coil, 20 the arrangement being such that normally the first-named plunger portion lies on the side of the transverse member opposite said plug and is moved into engagement with said plug upon the energization of the relay.
- 25 8. In a relay, a pair of coils arranged in axial alinement, a frame of magnetic material surrounding said coils, a transverse frame member separating said coils from each other, a plug extending from one end 30 of said frame into one of the coils and toward said transverse frame member, a plunger having a portion arranged to be acted upon by the latter coil, and a second portion adapted to be acted upon by the other coil, 35 the arrangement being such that normally the first-named plunger portion lies on the side of the transverse member opposite the said plug and is moved into engagement with said plug on energization of the relay, 40 and means for varying the position of the second plunger portion with relation to the first plunger portion.
9. In a relay, a pair of coils arranged in axial alinement, a frame of magnetic material surrounding said coils, a transverse frame member separating said coils from each other, a fixed stop, a plunger having a portion adapted to be acted upon by one of said coils and a second portion adapted to 45 be acted upon by the other coil, the arrangement being such that normally the first-named plunger portion lies on the side of the transverse member opposite its corresponding coil and is moved into that coil and into engagement with said stop upon the energization of said relay, and means for varying the position of the second plunger portion with relation to the first plunger portion.
10. In a relay, a pair of axially alined 50 coils, a plunger having a portion adapted to be acted upon by one of said coils and lying normally out of the field of said latter coil, a second plunger portion adapted to be acted upon by the other coil and lying normally in position to be influenced by that coil, 65 means for moving said latter plunger portion toward and from the other plunger portion, and a fixed stop, the arrangement being such that when the relay is energized said first-named plunger portion is moved into 70 the field of its coil and into engagement with the stop.
11. In a relay, a plunger, a lifting coil, a contact plate of magnetic material yieldingly supported by said plunger, fixed contacts of magnetic material with which said first mentioned contact plate engages, and a blowout coil surrounding each of said fixed contacts and electrically connected in series therewith.
12. A switch, comprising a movable contact disk, a pair of fixed contacts, each composed of a strip of magnetic material having a body portion and an in-turned lip for engagement with said movable contact disk, 85 and electroresponsive means for magnetizing said fixed contacts.
13. A switch, comprising a movable contact and fixed contacts coöperating therewith, said fixed contacts being composed of 90 strips of magnetic material having portions arranged in planes parallel to the direction of movement of the movable contact and having in-turned lips arranged to engage with said movable contact, and electroresponsive means for magnetizing said fixed contacts.
14. A switch, comprising fixed and movable contacts composed of magnetic material, said fixed contacts consisting of strips 100 having portions arranged parallel to the direction of movement of the movable contact and having in-turned lips arranged to engage with said movable contact, and electroresponsive means for magnetizing said fixed 105 contacts.
15. A switch, comprising coöperating fixed and movable contacts composed of magnetic material, said fixed contacts consisting of strips having portions arranged 110 in parallel to the direction of movement of the movable contact and having in-turned lips arranged to engage with said movable contact, and blow-out coils in series with said fixed contacts.
- In witness whereof, I have hereunto set my hand this 16th day of April, 1906.
